UNITED STATES PATENT OFFICE.

CHARLES HAROLD HEATHER, OF LEICESTER, ENGLAND, ASSIGNOR TO UNITED SHOE MACHINERY COMPANY, OF PATERSON, NEW JERSEY, A CORPORATION OF NEW JERSEY.

SOLE-ROUNDING MACHINE.

1,126,209.

Specification of Letters Patent. Patented Jan. 26, 1915.

Application filed October 7, 1912. Serial No. 724,426.

To all whom it may concern:

Be it known that I, CHARLES H. HEATHER, a subject of the King of England, residing at Leicester, in the county of Leicester, England, have invented certain new and useful Improvements in Sole-Rounding Machines; and I do hereby declare the following to be a full, clear, and exact description of the invention, such as will enable others skilled 10 in the art to which it appertains to make and use the same.

The present invention relates to machines for operating upon soles before they have been incorporated in a boot or shoe and 15 more particularly to machines of this type which determine the contour of the sole by rounding or otherwise trimming the edge of the sole.

The object of the present invention is to 20 provide means for enabling the sole to be quickly and accurately positioned in the proper operative relation to the pattern and trimming knife.

With this object in view, one feature of 25 the invention consists in the provision in a machine of this type of a positioning device having a member that contacts with the edge of the pattern and a sole gage adjustable relative thereto, the position of which is 30 automatically determined by the engagement of the member with the pattern edge.

A further feature of the invention consists in the combination with a pattern and coöoperating clamping head of a gage member 35 for positioning the sole upon the pattern arranged to move out of engagement with the sole upon a downward movement of the clamping head into an operative position.

Still further features of the invention 40 consist in certain novel features of construction, combinations and arrangements of parts hereinafter described and claimed, the advantages of which will be obvious to those 45 skilled in the art from the following description.

In the accompanying drawings illustrating the preferred form of the invention; Figure 1 is a side elevation of a portion of 50 a rounding machine embodying the several features of the invention in their preferred form; Fig. 2 is a detail illustrating an end elevation of the sole positioning gages and actuating mechanism therefor; and Fig. 3 55 is a side elevation partly in section of the

sole positioning gages and actuating mechanism.

The illustrated embodiment of the invention is shown in connection with a machine of the type disclosed in the patent to Mayo, 60 882,009, March 17, 1908. This machine comprises a pattern 1 which corresponds to the desired shape of the sole and upon which the sole is supported during the operation of the machine. The edge of the sole is 65 trimmed or rounded by a knife 2 which is guided by the edge of the pattern and is caused to automatically traverse around the pattern to trim the entire sole edge. The sole, indicated at 3, is clamped in position 70 upon the pattern by a clamping head 5 which is supported upon the lower end of a slide 6 movable vertically in bearings formed in an arm 7. The vertical slide 6 is actuated in the usual manner by a lever 8 pivot- 75 ed at 9 in the arm 7 and connected at its opposite ends to the slide 6 and to a suitable treadle not shown. Upon depressing the treadle the clamping member is moved downwardly to clamp the sole firmly upon 80 the pattern in which position it is held during the operation of the machine.

It is desirable in order to facilitate the proper positioning of the sole upon the pattern and to enable the sole to be trimmed 85 evenly around its entire edge that positioning devices be provided which shall accurately determine the relation between the block sole and pattern. In the present invention the positioning device is removed 90 from contact with the sole and pattern upon the movement of the clamping head into an operative position, thus allowing the knife to traverse freely around the entire edge of the sole without interference with the gage. 95 In the simplest and most efficient form of the invention which has yet been devised, this is accomplished by providing suitable connections between the gage member and clamping head to cause the gage member to 100 swing outwardly into an inoperative position upon a downward movement of the head into engagement with the sole. In the illustrated embodiment of the invention a pair of gage members 10 are provided which 105 act in conjunction with the knife 2 to position the sole at three separate points remote from one another. Each gage device is pivoted at 12 in a bracket 13 secured to the arm 7 and is arranged with its lower free end 110

resting against the edge of the pattern 1. The upper end of the gage member 10 is provided with an extension 15 above the pivot 12 that engages with a spring plunger 5 seated in the bracket 13 and operating to normally retain the lower end of the gage member in contact with the pattern. Each gage member is moved outwardly upon a downward movement of the clamping head 10 by a link 17 which connects the clamping head and a laterally extending arm 18 secured to the gage member. The link 17 and arm 18 are provided with a pin and slot connection indicated at 20 in order that the preliminary downward movement of the clamping head 5 shall not impart a corresponding outward movement to the gage members. With this construction, there is a predetermined amount of lost motion in the connections between the clamping head and gage members so that the gage member is not swung outwardly until the clamping member has substantially completed its downward movement and is in position to clamp the sole upon the pattern.

It is oftentimes desirable to vary the extension of the block sole beyond the edge of the pattern and to this end the positioning device consists of a member for engaging the edge of the pattern and a sole gage which is adjustable relative thereto. The gage member 10 is provided at its lower end with an inturned foot 21 which contacts with the edge of the pattern and serves to space the member 10 away from the edge of the pattern. The sole gage consists of a resilient strip 22 secured to the gage member 10 at its upper end and contacting at its lower free end with an adjusting screw 23 threadedly mounted in the gage member. With this construction and arrangement, the position of the sole edge is automatically determined with relation to the edge of the pattern when the sole is placed thereon and this relation may be varied as desired by a simple adjustment of the screw 23.

While it is preferred to employ the specific construction and arrangement of parts shown and described, it will be understood that this construction and arrangement is not essential except so far as specified in the claims and may be changed or modified without departing from the broader features of the invention.

55 The invention having been described, what is claimed is:—

1. A sole rounding machine having, in combination, a pattern, a trimming knife, a clamping head coöperating with the pattern, and a gage member for positioning the sole

upon the pattern arranged to move out of engagement with the sole upon a movement of the clamping head into an operative position.

2. A sole rounding machine having, in combination, a pattern, a trimming knife, a clamping head coöperating with the pattern, a gage member for positioning the sole upon the pattern, and connections between the gage member and clamping head for moving the gage member out of contact with the sole upon a movement of the clamping head into operative position.

3. A sole rounding machine having, in combination, a pattern, a trimming knife, a clamping head coöperating with the pattern, a gage member pivotally supported at its upper end and arranged to contact with and position the sole at its lower free end, and means for moving the gage member outwardly as the blank is clamped in position to avoid interference with the trimming knife.

4. A sole rounding machine having, in combination, a pattern, a trimming knife, a vertically movable clamping head, a gage member pivotally supported at its upper end, means for causing the lower end of the gage member to normally contact with the edge of the pattern, and connections between the clamping head and gage member to move the gage member outwardly upon a downward movement of the clamping head into operative position.

5. A sole rounding machine having, in combination, a pattern, a trimming knife, a vertically movable clamping head, a gage member normally retained in contact with the pattern, and connections between the gage member and clamping head having a predetermined amount of lost motion to cause the gage member to remain in contact with the pattern until the clamping head has moved substantially into operative position.

6. A sole rounding machine having, in combination, a pattern, a trimming knife, a clamping head coöperating with the pattern, a gage member having a foot at its lower end arranged to contact with the pattern edge, a resilient strip secured at one end to the gage member, and means for adjusting the free end of the strip with relation to the foot in order to vary the position of the sole edge relative to the edge of the pattern.
